(57) CLAIM

The ornamental design for a food serving bowl, as shown and described.

DESCRIPTION

FIG. 1 illustrates a perspective view of a food serving bowl employing the ornamental design in accordance with the invention;

FIG. 2 illustrates a top view of the food serving bowl of FIG. 1;

FIG. 3 illustrates a bottom view of the food serving bowl of FIG. 1; and,

FIG. 4 illustrates a side elevation view of the food serving bowl of FIG. 1 (each side being the same as that shown).
